UNITED STATES PATENT OFFICE

168,083

PRINT UNIT FOR PRINTING MACHINES

William Wockenfuss, Brooklyn, N. Y., assignor to
Burroughs Adding Machine Company, Detroit,
Mich., a corporation of Michigan

Application May 29, 1952, Serial No. 20,109

Term of patent 14 years

(Cl. D64—11)

To all whom it may concern:

Be it known that I, William Wockenfuss, a citizen of the United States, residing at Brooklyn, New York, have invented a new, original, and ornamental Design for a Print Unit for Printing Machines, of which the following is a specification, reference being had to the accompanying drawing, forming a part hereof.

Fig. 1 is a perspective view showing the top, front and one side of a print unit for printing machines, embodying my new design; and

Fig. 2 is a perspective view showing the top, rear and other side thereof.

I claim:

The ornamental design for a print unit for printing machines, substantially as shown.

WILLIAM WOCKENFUSS.
